DESIGN FOR A TOY BUILDING

Walker W. Tackett, North Hollywood, Calif.

Application April 24, 1944, Serial No. 113,355

Term of patent 7 years

(Cl. D34—15)

To all whom it may concern:

Be it known that I, Walker W. Tackett, a citizen of the United States, residing at North Hollywood, in the county of Los Angeles and State of California, have invented a new, original, and ornamental Design for Toy Buildings, of which the following is a specification, reference being had to the accompanying drawings, forming part thereof.

Fig. 1 is a side perspective view of a toy building showing my new design; and

Fig. 2 is an opposite side perspective view thereof.

I claim:

The ornamental design for a toy building, as shown.

WALKER W. TACKETT.
